UNITED STATES PATENT OFFICE

SADIE GREENWALD, OF BROOKLYN, NEW YORK

LIPSTICK CASE AND FABRIC WIPER

Application filed April 3, 1930. Serial No. 441,269.

My invention relates to what I call a lipstick "spread". By this term I mean a device whereby excess of lipstick may be removed or the lipstick material spread over the lips. Frequently the end of the finger is used for this purpose but since this leaves some of the material of the lipstick on the finger it is at best a messy operation and the fingers are frequently wiped on a handkerchief or towel which leaves stains somewhat difficult to remove.

The object of my invention is to do away with the use of the finger for this purpose and to provide a substitute in the shape of a small, sanitary and handy device for wiping off excess of lipstick or spreading it properly. The invention is not necessarily confined to lipstick material but may also be used to spread rouge and a feature of my invention is the employment of a soft fabric carried over a support or pad preferably shaped like a finger, and means whereby the fabric may be moved as desired to always present a fresh surface for use.

Other features and advantages of the invention will become apparent from the following detailed description and claims when taken in connection with the accompanying drawings, in which

Figure 1 is a front elevation of my device;

Figure 2 is a longitudinal section on the line 2-2 of Figure 3;

Figure 3 a section on the line 3-3 of Figure 1;

Figure 4 a section on the line 4-4 of Figure 2;

Figure 5 is a top view of Figure 3 with the cover removed;

Figure 6 is somewhat similar to Figure 3 but shows a modified construction whereby the tape is guided;

Figure 7 is a further modification shown in sectional view; and

Figure 8 is a view partly broken away on the line 8-8 of Figure 7.

Referring to the drawings, Figure 1 shows my device in combination with a lipstick holder of the usual type, the numeral 22 indicating the casing of my device proper, while

4 indicates the casing of the lipstick holder, the lipstick protruding at 6.

For convenience it is advantageous to have the two in combination, although my device is intended for separate manufacture and use as well as in combination.

Referring now to Figures 2 and 3 it will be noted that there is an inside frame and a casing, said inside frame having side pieces 8, or legs, arranged parallel with each other. The upper part of this frame is formed as indicated at 10, 11 and 12, thus providing a groove for supporting a pad 14. This upper portion of the frame is curved in both directions so that the end of the pad assumes approximately the shape of the end of the finger, portions of the frame shown at 16 being bent inwardly a little to properly secure the pad in place as shown at Figure 3. The lower portion of the frame is bent outwardly and formed into a circular ring as shown at 18 and this is provided with a rib 19. The ring is split at 20, Figure 3, to permit it to have the necessary springiness and thereby enable it to receive the casing 22. This casing also has a circular groove 24 which fits the rib 19 which securely holds the casing in place. The casing 4 of the lipstick holder may be so shaped as to fit over the circular portion or ring of the casing 22 and is split at 21 for this purpose.

The pad 14 serves as a support or backing about which the fabric which is to be used for spreading the lipstick material is passed. This fabric, which may be of any suitable material, is supplied from a roll supported on a shaft or spindle 26 carried in the side pieces 8. These side pieces have oblique slots 27 so that the shaft 26 with its supply of fabric may be dropped into place after the casing 22 has been removed.

Situated below the spindle 26 is a take-up spindle 30 supported by the parallel sides or legs 8 of the inner frame. This spindle extends beyond the outer casing 22 where it is provided with a knob 32 whereby the spindle may be turned. The casing 22 is slotted as indicated at 23 to permit it to fit over the spindle. The strip of material or fabric passes from the supply roll up over the

pad as shown at 28, Figure 3, and its end is passed through a slot in the spindle 30 of the take-up roll. As this roll is turned by the knob 32 the fabric is wound on the spindle 30, as will be readily understood.

In the form of device as shown in Figure 3 the down pass of the tape or strip presses against the supply roll when the amount of material on this roll is large as compared with the amount on the take-up roll, but in the modification shown in Figure 6 the inner frame is modified to provide a projecting tongue 34 which tongue forms a guide for the lower portion of the strip as it passes

10 down from the end of the pad and around the take-up spindle 30 and prevents contact with the material of the supply roll at all times. Otherwise the construction of Figure 6 is the same as that described in connection with Figures 1, 2 and 3. It may be noted that in Figure 6 instead of having the ordinary lipstick holder attached its place is taken by a bottom cap 35.

In the construction shown in Figures 7 25 and 8 I have widened the outside casing 22 so as to provide room for a pulley 36 connected to the end of the spindle 26 and I have also provided a similar pulley 38 on the spindle 30. These pulleys act to guide a very narrow 30 steel wire or tape 40 shown in side elevation in Figure 8, and this acts to unwind the fabric from the supply roll as it is wound up on the take-up roll without causing any strain on the fabric itself. I thus provide means 35 independent of the fabric for moving the fabric over the end of the pad.

In Figure 7 the end of the pad 14 is rounded in one direction only forming a cylindrical surface over which the fabric 28 passes.

40 Friction washers 44 and 45 are provided for the spindles 26 and 30 respectively to prevent the spindle turning too easily.

By reason of the oblique slots 27 a new supply roll can be inserted at any time.

45 The operation of the device will be apparent from the foregoing description since turning of the knob 32, whether in one form of device or the other, will cause the fabric to move over the pad and a fresh surface may 50 always be made available for use. It will be seen that the device is used very much as the finger would be in spreading the lipstick material over the lips or for spreading rouge. It is also to be used for wiping off any excess 55 material. A cover 42 frictionally engages the outside casing, which cover has a circular portion 43 bent inwardly and so spaced that it engages the end of the outside casing to limit the downward movement of the cover 60 so that it does not touch the fabric, thus always providing a device which is entirely free from dust or contamination from any outside source.

It is to be understood that variations may 65 be resorted to, all within the scope of the

invention without departing from the spirit thereof.

What is claimed as new is:

1. A lipstick spreader having a support for a wiping or spreading fabric, said support being shaped like a finger and means for moving a fabric over the support. 70

2. A spreader for lipstick comprising a frame, a roll of wiping fabric supported therein, a spindle upon which the fabric may be wound from the supply roll, and a support for the fabric carried above the supply roll and over which it passes to the re-wind roll. 75

3. A spreader for lipstick comprising a frame, a roll of wiping fabric supported therein, a spindle upon which the fabric may be wound from the supply roll, a support for the fabric carried above the supply roll and over which it passes to the re-wind roll, 80 and means for preventing the return run of the fabric from engaging the supply roll. 85

4. A spreader for lipstick comprising a frame, a roll of wiping fabric supported therein, a spindle upon which the fabric may be wound from the supply roll, a support for the fabric carried above the supply roll and over which it passes to the re-wind roll, 90 and means independent of the fabric for moving the supply roll from the take-up roll. 95

5. A lipstick spreader having a support for a wiping or spreading fabric, said support being shaped like a finger, and a fabric movable over the support.

Signed at New York, New York, this 31st 100 day of March, 1930.

SADIE GREENWALD.
